UNITED STATES PATENT OFFICE.

HENRY G. M. HOWARD, OF KALAMAZOO, MICHIGAN.

TWO-WHEELED VEHICLE.

SPECIFICATION forming part of Letters Patent No. 341,144, dated May 4, 1886.

Application filed February 9, 1886. Serial No. 191,268. (No model.)

To all whom it may concern:

Be it known that I, HENRY G. M. HOWARD, a citizen of the United States, residing at Kalamazoo, county of Kalamazoo, State of Michigan, have invented a new and useful Two-Wheeled Vehicle, of which the following is a specification.

This invention has for its object improvements in that well-known class of two-wheeled vehicles used in horse-training.

In the drawings forming a part of this specification, Figure 1 is a side elevation; Fig. 2, a top view of about one-half of the vehicle; Fig. 3, an enlarged view of details in Fig. 1, referred to by like letters; and Fig. 4 is a section on line 11 in Fig. 2, enlarged.

Referring to the letters marked on the drawings, *a* is the axle; *B*, the wheels; *D*, the thills, and *c* the thill cross-bar, like these parts in prior constructions. Of course it will be understood that the constructions on both sides of the vehicle are alike, the figures in the drawings showing one side.

The body is formed from bars *A* and cross-braces *a'*, the rear end of said bars *A* bearing the seat *C*. The body pivotally connects with the cross-bar *c*, or with the thills, if preferred, on both sides, by means of shackles *c'*. From thence it extends rearwardly, and curves downwardly and rearwardly and upward over the axle, where it bears the seat *C*, as in prior constructions. Of course the form of the body may be varied so long as it admits of the driver sitting in the seat with his feet down in the body in the ordinary natural position.

The body may have a solid floor, or the driver may rest his feet on the braces *a'*, or otherwise, as desired.

The cross-bar *c* at each end has two branches in the ordinary manner. The body is attached to the forward branch in the illustration shown.

Near the rear branch of the cross-bar the body is provided with open-top pockets, *e*, containing the spiral springs *r*. These pockets may be walled on the sides by bars, as shown, or they may be walled all the way around. The walls of these pockets keep the springs from bulging laterally. Thus no center rod is needed in the springs, the entire weight of the body being suspended by the springs themselves. The weight of the body and its load expands the springs, thus securing the full and most desirable elastic effect of the springs. The lower ends of the springs are attached to the body in the bottom of the pockets *e*, and the upper ends of said springs are attached to the rear branch of the cross-bar *c*. When the body is borne down by the weight of the rider, the springs expand and are canted to an oblique angle, their lower end swinging forward, and this movement of the body canting the pockets at the same angle. Thus the springs *r* should be pivotally attached to the cross-bar at their upper end, as at *v*, Figs. 1 and 3.

Having thus described my invention, what I claim as new, and desire to secure by Letters Patent, is—

In a two-wheeled vehicle, the combination of the thills, the vehicle-body provided with the open-top pockets for containing the springs in the rear of the front fulcrum of the body, and spiral springs in said pockets forming immediate attachment at their lower ends with the body, and at their upper ends with the thill cross-bar, substantially as set forth.

In testimony of the foregoing I have hereunto subscribed my name in presence of two witnesses.

HENRY G. M. HOWARD.
